(57) **CLAIM**

The ornamental design for a curtain holdback tie, as shown and described.

DESCRIPTION

FIG. 1 is a perspective view of a curtain holdback tie, shown open in a first configuration;

FIG. 2 is a front elevation view thereof; a rear elevation view, a top plan view, and a bottom plan view being the same;

FIG. 3 is a left side elevation view thereof; the right side elevation view being the same; and,

FIG. 4 is a front elevation view thereof, shown closed in a second configuration.

The broken lines represent portions of the structure that forms no part of the claim.
